F. M. WOOD,
VEHICLE SIGNAL;
APPLICATION FILED APR. 26, 1917.

1,269,241.

Patented June 11, 1918.

INVENTOR
FRANK M. WOOD
BY
C. F. Blake ATTY.

UNITED STATES PATENT OFFICE.

FRANK M. WOOD, OF PORTLAND, OREGON.

VEHICLE-SIGNAL.

1,269,241.

Specification of Letters Patent. Patented June 11, 1918.

Application filed April 26, 1917. Serial No. 164,805.

To all whom it may concern:

Be it known that I, FRANK M. WOOD, a citizen of the United States, residing at Portland, county of Multnomah, State of Oregon, have invented certain new and useful Improvements in Vehicle-Signals, of which the following is a specification.

My invention relates to vehicle signals in general, and particularly to that class of such signals as are used upon automobiles and the like.

The objects of my invention are to produce such a device as will announce to the persons near a moving vehicle the intentions of the driver thereof as to making turns; that shall be simple and easy to operate, and shall be cheap to manufacture.

I accomplish the above objects by means of the construction illustrated in the accompanying drawing, which therefore becomes a part of this application for Letters Patent, like characters of reference indicating like parts throughout the several views thereof, and in which:

25 Figure 1 is a perspective view of my device.

Fig. 2 is a detailed elevation of the head of my device, parts being removed to best illustrate the construction.

30 Fig. 3 is a sectional plan upon line 3—3 of Fig. 2.

Fig. 4 is a detailed plan view of the operating yoke.

Fig. 5 is an elevation of the operating yoke.

As illustrated my device is intended to be clamped upon the side of the dash board of the vehicle by means of a clamp having jaws 6 and 7 and a clamping screw 8.

40 To carry the visible signal portion of my device outward beyond the dash board to a position from which it may easily be seen from all surrounding points I provide an arm 9, preferably integral with jaw 7, and 45 terminating in an upwardly turned portion or head 10.

Threaded into said head 10 I provide a spindle 11 which forms the pivot about which the signal arms 12 rotate.

50 Each signal arm is integral with a hollow semi-conical shell or hub 13 which surrounds spindle 11, there being bearings 14 at each end thereof for said spindle, as shown in Fig. 2.

55 Each of said hubs 13 has thereon a lug 15 diametrically opposite the arm 12 there-

on, and offset from said arm a distance substantially equal to the thickness thereof, so that when said hubs are placed together to encompass the spindle 11 with their respective arms 12 in alinement, as shown in Fig. 1, the lugs 15 will register respectively with the arms, and may be bolted thereto by bolts 16, as shown in Fig. 1, said bolts thereby securing the two arms 12 pivotally upon 65 spindle 11.

To rotate the arms upon spindle 11 I provide bosses 17 upon the lower ends of the hubs 13, which bosses coact when the arms are in place upon spindle 11 to form an eccentric cam, as shown in Figs. 1 and 3.

To operate the said cam I provide a double armed L-shaped yoke pivotally mounted upon head 10 by means of rod 18 which is journaled in bearings 19 and 20 respectively integral with rod 9 and head 10.

A handle 21 is formed upon the end of rod 18 whereby the device is manually operated.

The operating yoke consists of a hub 22 secured upon rod 18; arms 23 extending therefrom upon each side thereof substantially normal to rod 18; forwardly extending arms 24 respectively integral with arms 23, 85 in the same plane therewith, and normal thereto, said arms 24 receiving therebetween the head 10; upwardly extending curved arms 25 respectively integral with arms 24, said arms 25 curving upward toward each 90 other in a plane substantially parallel with said head 10; and a curved yoke 26 uniting the adjacent ends of arms 25, said yoke being disposed in a substantially horizontal plane, and being adapted to encompass and 95 coact with the cam formed by bosses 17, as shown in Fig. 1.

Oscillation of rod 18 rotates the operating yoke attached thereto and causes yoke 26 to rotate the cam formed by bosses 17, thus 100 rotating the arms 12 about the spindle 11 to indicate the intended movement of the vehicle.

To return the arms to their initial position after operation thereof I provide a 105 spring within the hubs 13 mounted upon spindle 11, and secured thereon by passing the respective spring ends 27 therethrough, as shown in Fig. 2.

The spring is wound about the spindle 11 110 right-handedly from one of said ends, and left-handedly from the other of said ends,

the central portion of said spring being bent outwardly from spindle 11 to form a loop 28 adapted to encompass one of the screws 16 and lie between one of the arms 12 and 5 bosses 15, as shown in Fig. 2.

My invention may be made of any size and constructed of any material deemed convenient and suitable in a device of this character, and while I have illustrated and 10 described a form of construction and arrangement of parts found desirable in materializing my invention, I wish to include in this application for Letters Patent all mechanical equivalents and substitutes that 15 may fairly be considered to come within the scope and purview of my invention as defined in the appended claims.

Having disclosed my invention so that others skilled in the art may be enabled to 20 construct and to use the same, what I claim as new and desire to secure by Letters Patent is:—

1. A vehicle signal comprising a clamp; an arm integral with said clamp; a head 25 upon said arm; a signal rotatably mounted upon said head; a cam integral with said signal; a yoke coacting with said cam; and means to operate said yoke.

2. In a vehicle signal a pair of rotatably 30 mounted members each consisting of an arm, a hub, and a half cam; said half cams coacting to form a complete cam when said members are secured in place; a spindle upon which said members are pivotally 35 mounted; a yoke substantially surrounding said spindle and coacting with said complete cam; and means to operate said yoke.

3. In a vehicle signal, an arm; a spindle

upon said arm; a cam rotatably mounted upon said spindle; a pivotally mounted yoke 40 adjacent said spindle adapted to coact with and to rotate said cam; a signal arm mounted upon said cam; and means to operate said yoke.

4. In a vehicle signal, a spindle; a pivotally mounted yoke surrounding said spindle and consisting of a hub; oppositely and transversely disposed arms extending from said hub, longitudinal members forwardly extending from the extremities of each of 50 said arms, curved arms upwardly extending from the extremities of each of said members, and a horizontally curved member uniting the extremities of said curved arms; a cam pivotally mounted upon said spindle 55 and encompassed by said horizontally curved member; a signal arm mounted upon said cam; and means to rotate said yoke.

5. A vehicle signal comprising a clamp; an arm; an operating rod rotatably mounted 60 upon said arm substantially parallel therewith; a spindle upon the outer extremity of said arm; a yoke secured upon the outer extremity of said rod and encompassing said spindle; a cam rotatably mounted upon said 65 spindle and coacting with said yoke; and a signal arm mounted upon said cam.

In witness whereof I claim the foregoing as my own I hereunto affix my signature in the presence of two subscribing witnesses, at 70 Portland, county of Multnomah, State of Oregon, this 13th day of April, 1917.

FRANK M. WOOD.
